UNITED STATES PATENT OFFICE.

LOUIS STREBEL, OF BERGENFIELD, NEW JERSEY.

CAP-FEEDER FOR BOTTLE-CAPPING MACHINES.

1,106,590.

Specification of Letters Patent.

Patented Aug. 11, 1914.

Application filed June 13, 1913. Serial No. 773,402.

To all whom it may concern:

Be it known that I, LOUIS STREBEL, a citizen of the United States of America, residing in Bergenfield, in the county of Bergen and State of New Jersey, have invented certain new and useful Improvements in Cap-Feeders for Bottle-Capping Machines, of which the following is a specification.

This invention relates to an improved 10 cap-feeder for bottle-capping machines by which the caps are fed in a reliable manner from the supply-hopper to the capping die; and for this purpose the invention consists of a cap-feeder for the capping machine which comprises a feed-hopper, a receiving compartment below the same, a semicircular guard-plate in the upper part of the compartment, a rotary feed-cone provided with a paddle and a supply-opening 20 adjacent to the paddle for taking up the caps from the feed-compartment, said cone having a flange, and a feed-disk forming a channel with the flange for conducting the caps to a feed-chute.

25 The invention consists further of certain details of construction which will be fully described hereinafter and finally pointed out in the claims.

In the accompanying drawings, Figure 30 1 represents a side-elevation of my improved cap-feeder for bottle-capping machines, Fig. 2 is a vertical longitudinal section of the same on line 2—2, Fig. 4, Figs. 3 and 4 are vertical transverse sections on 35 lines 3—3 and 4—4, Fig. 2, Fig. 5 is a perspective view of the feed-cone shown detached, Fig. 6 is a perspective view of the feed-disk, Figs. 7 and 8 are detail vertical sections, drawn on a larger scale, of the delivery-channel for the caps, Fig. 7 showing 40 a cap which is fed in inverted position, and Fig. 8 a cap which is fed in the required position so as to permit it to pass to the feed-chute, and Fig. 9 is a top-view of a 45 bottle-cap of any approved construction as usually fed.

Similar letters of reference indicate corresponding parts throughout the different figures of the drawings.

50 Referring to the drawings, h represents the hopper and c the intermediate feed-compartment, which is supported in stationary position on a bracket c^1 at the upper end of the pillar p of the bottle-capping machine. The hopper is connected with the compartment c by means of a tube h^1 . In

the compartment c is arranged a semicircular guard-plate b , which is attached at its upper end to the tube or throat h^1 and which extends to the sleeve-shaped supporting bearing h^2 for the rotary feed-cone, said bearing being cast integral with the rear-wall of the compartment c , and said sleeve supporting a shaft s to which rotary motion is imparted by a bevel-gear transmission g , g^1 and a gear-wheel transmission g^2 , g^3 , the bevel-wheel g^1 and gear-wheel g^3 being on a common hub and freely rotatable together on the pillar p . The gear-wheel g^2 is applied to the upper end of an 60 upright shaft s^1 to which motion is imparted by means of gear-wheels g^4 , g^5 . A cam-disk g^6 , connected with the gear-wheel g^5 , imparts vertically-reciprocating motion to the capping plunger d of the capping 65 die d^1 , which is shown and described in a separate application for Letters Patent filed by me at the same time herewith. The motion-transmitting shaft s^1 is supported in bearings of brackets e , e^1 supported on the 70 upright pillar p .

To the rotary shaft s is applied, adjacent to the supporting bearing, the hub f^1 of a cone-shaped hopper f , which is rotated in a cylindrical extension c^2 of the 75 compartment c . The feed-cone f is provided at one point of its circumference with an opening o , and with a radial paddle o^1 adjacent one edge of the opening, the paddle serving for taking along caps accumulated 80 in the bottom of the compartment c and lifting them along the side of the compartment until they fall through the opening o to the interior of the feed-cone f . From the interior of the feed-cone the caps fall into 85 a circular channel formed between a circumferential flange f^2 of the cone and a feed-disk f^3 , which is supported on the end of the shaft s between a shoulder f^4 at the inside and a screw-nut f^5 and washer f^6 at the outside of the disk. The circumferential channel f^9 formed between the flange f^2 and the disk f^3 is closed by a laterally-extending circumferential flange f^7 of the compartment. The lower part of the channel f^9 is connected by a chute a with the lower end of the capping die d^1 , the upper end of the chute being attached to a lug at the lower part of the compartment c , as shown clearly in Fig. 2. The cone-flange is provided near the 100 outer portion of the channel f^9 with an inclined shoulder i . A shoulder i^1 is provided

on the circumference of the disk, and a second shoulder i^2 opposite the lower edge of the inclined shoulder i . An annular depression i^3 is made in the disk between the 5 last-named shoulder and the outer edge of the disk f^3 , as shown clearly in Figs. 7 and 8. This configuration of the channel f^3 with the cap-selective elements arranged in the direction of discharge of the cap, namely 10 from inside toward outside of the drum, permits the passage of the caps e fed into the chute a , as shown in Fig. 7, without being obstructed in their delivery; while when a cap is fed in inverted position, shown in 15 Fig. 8, it cannot pass through the channel, but is carried along by the rotating cone and disk, and when by rotation that part of the cone and disk arrives again at its upper position the wrongly placed cap falls down- 20 ward, in return direction, in the channel f^3 , back into the interior of the feed-cone, where it undergoes agitation with the other caps therein and is fed again to the channel f^3 , in either correct or reversed position, ac- 25 cording to its chance arrangement at the instant of feeding. A second opening is pro- 30 vided in the feed-cone, as shown in Fig. 4, said opening o^2 serving to permit discharge from the cone of those caps not introduced into the channel f^3 . By this construction of 35 the annular channel between the disks f^1 and f^3 , the caps are fed in the position required for the capping die in a reliable manner, and a sufficient supply of caps is pro- 40 vided at all times even when the capping machine is working at high speed.

I claim:

1. A cap-feeder for bottle-capping machines, which comprises a hopper, a feed- 40 compartment below the hopper, an inclined guard-plate in said compartment, a rotary feed-cone in the compartment provided with a paddle at its circumference and an opening adjacent to said paddle, said cone being 45 provided with a circumferential flange, and a feed-disk in front of the flange of the feed-cone forming a channel with said flange, and a delivery-chute for the caps connected with the lower part of the feed- 50 compartment.

2. A cap-feeder for bottle-capping machines, which comprises a feed-hopper, a feed-compartment connected therewith, a delivery-chute at the lower end of said com- 55 partment, a rotary feed-cone in said compartment provided with an opening and a fixed paddle adjacent said opening for transmitting caps from the feed-compartment to

the feed-cone, a flange at the larger end of the feed-cone, and a disk in front of said feed-cone and rotating with the same, said flange and disk forming between them an annular throat for permitting the delivery of the caps when in proper position, but preventing delivery and returning the caps into 60 the feed-cone when in inverted position.

3. A cap-feeder, comprising a stationary feed-compartment, a rotary feed-cone having an inlet-opening therefrom, means carried by said feed-cone for picking up a 70 limited quantity of caps from said compartment at each rotation thereof and guiding them into said cone through the inlet-opening, an outlet-opening in said feed-cone adapted to discharge caps therefrom into 75 said compartment, said outlet-opening being spaced from the inlet-opening, and cap-selective means coöperating with said feed-cone.

4. A cap-feeder, comprising a stationary feed compartment, a rotary feed-cone having an inlet-opening therefrom, means carried by said feed-cone for picking up a limited quantity of caps from said compartment at each rotation thereof and guiding them into said cone through the inlet-opening, an outlet-opening in said feed-cone adapted to discharge caps therefrom into 85 said compartment, said outlet-opening being spaced from the inlet-opening and located in the periphery of the cone, and cap-selective means coöperating with said feed-cone.

5. A cap-feeder, comprising a stationary feed-compartment, a rotary feed-cone having a peripheral inlet therefrom, said feed-compartment extending below said feed-cone and said inlet-opening thereof, means carried by said feed-cone for picking up a limited quantity of caps from said compartment at each rotation of the cone and guiding them therein through said inlet-opening, an outlet-opening in the periphery of 100 said feed-cone, spaced from the inlet-opening and adapted to discharge caps at each 105 rotation thereof into said compartment below the cone, and cap-selective means co-operating with said feed-cone.

In testimony, that I claim the foregoing as my invention, I have signed my name in 110 presence of two subscribing witnesses.

LOUIS STREBEL.
